COMBINED TOWING ARM BASKET AND CARRY- ING FRAME FOR A BICYCLE TRAILER

Vincent J. Hlavin, 2741 Chesterton Road,
Shaker Heights, Ohio 44122

Filed Feb. 4, 1972, Ser. No. 223,803

Term of patent 14 years

Int. Cl. D12—11

U.S. Cl. D12—158

Fig. 1

Fig. 2

FIG. 3

FIG. 4

FIG. 1 is a perspective view of a combined towing arm basket and carrying frame for a bicycle trailer embodying my new design;

FIG. 2 is a side elevational view, the opposite side being substantially a mirror image thereof;

FIG. 3 is a top plan view; and

FIG. 4 is a front elevational view.

The broken lines shown in the drawings are for illustrative purposes only.

I claim:

The ornamental design for a combined towing arm basket and carrying frame for a bicycle trailer, as shown and described.
